UNITED STATES PATENT OFFICE.

JOHN COLLISON BROWN, OF NIAGARA FALLS, ONTARIO, CANADA.

FIRE-ESCAPE.

1,091,802.

Specification of Letters Patent. Patented Mar. 31, 1914.

Application filed January 2, 1913. Serial No. 739,796.

To all whom it may concern:

Be it known that I, JOHN COLLISON BROWN, of the city of Niagara Falls, in the county of Welland, in the Province of Ontario, Canada, have invented certain new and useful Improvements in Fire-Escapes, of which the following is the specification.

My invention relates to improvements in fire escapes and the object of the invention is to devise an appliance which may be readily placed in position in or removed from an upper story window of a building by firemen situated on the ground level of the building and by which people may be readily and safely lowered from such window and it consists essentially of a pole comprising a series of detachably connected lengths, and a supporting clutch mechanism at the top operated by a cord extending to the bottom of the pole, a suspending bracket supported by such clutch mechanism and designed to engage the window sill or other suitable support and then to be freed from the clutch mechanism, a basket suspended from the bracket and means for lowering the basket either operated from the ground or by the occupants of the basket and means operated from the ground for removing the suspended bracket as hereinafter more particularly explained.

Figure 1, is a front elevation of a portion of a building showing my device applied to a second story window. Fig. 2, is a vertical section through the building shown in Fig. 1 and showing my appliance attached to the window. Fig. 3, is an enlarged sectional detail of a window sill and my mechanism attached thereto. Fig. 4, is an enlarged perspective detail of the suspension bracket and means for placing it in position in the window. Fig. 5, is an enlarged perspective detail of the suspension bracket.

In the drawings like letters of reference indicate corresponding parts in each figure.

A is a portion of a building of which A' is the second story window provided with a window sill A² provided with the usual inner ledge A³.

B is a suspension bracket comprising a vertical plate B' designed, when in position, to rest against the front face of the window sill A².

B² is a loop bar provided with a hooked end B³ having a point B⁴.

B⁵ is a hinged plate pivoted at its lower

end in the loop B⁶ swung in the bracket B⁷ secured to the plate B'. The upper end of the plate B⁵ extends through the loop B² and is provided with a curved portion B⁸ 60 in which is formed a hole B⁹.

B¹⁰ is a pulley block connected by a link B¹¹ to the portion B⁸ by extending through the hole B⁹.

C is a basket by which the occupants of 65 the building may be lowered from an upper story window.

C' is a cross bar on which is swung the hook member C².

C³ is a cord connected at the lower end to 70 the hook member C² and extending over the pulley block B¹⁰ and down to the ground.

D is a pole provided at its upper end with the cross arm D'.

D² is a pulley journaled in the outer end 75 of the cross arm D'.

D³ and D⁴ are vertical pulleys journaled at the front end of the cross arm D'.

D⁵ and D⁶ are clutch members pivoted to the front end of the pole at D⁷ and D⁸. The 80 clutch members D⁵ and D⁶ are spring held together by the tension spring D¹⁰. The clutch members D⁵ and D⁶ are provided with tail pieces D¹¹ and D¹².

D¹³ is a cord secured to the tail pieces D¹¹ 85 and D¹² from which it extends between the pulleys D³ and D⁴ and over the pulley D² down to the ground.

E is a bracket secured to the front face of the pole D. The bracket is provided with 90 a hooked outer end E' and spring fingers E² opposing the same. The pole D may be made in a plurality of links connected together by a clamping bracket.

When it is desired to place my apparatus 95 in position all that it is necessary to do is to connect the suspension bracket B to the clutch members D⁵ and D⁶ as shown in Fig. 4, the loop B² thereof engaging between the hook E' of the bracket E and the spring 100 fingers E². In this position the bracket B is raised to the window level and the hooked end passed through the window. If the window is closed the point end B⁴ of the bracket will serve to break the window. 105

The hook B³ of the bracket will then engage with the window ledge A³ as shown in Figs. 2 and 3 and the cord D¹³ is then pulled by the firemen so as to throw the clutch members D⁵ and D⁶ into the position shown in 110 Fig. 5. The members of the suspension bracket will then be freed from such clutch

members and fall into the position shown in Fig. 3, the cord C³, of course, being attached to the bracket as shown in Fig. 3. The basket C may then be raised to the required height so that the people may escape out of the window.

For removing the suspension bracket B from the window so that it may be placed in another window in the building I provide the bracket F comprising the arms F' and F² having downwardly looped portions F³ and an upward extension F⁵ on which is journaled a spool F⁶ around which is wound the cord F⁷ having a hook F⁸.
15 When it is desired to remove the bracket B the fireman takes the bracket F up to the window and places it over the sill with the loops F³ and F⁴ extending over the edge A³ as shown in Fig. 3. The hook is then passed 20 through the eye D¹⁴ of the bracket B, the cord F⁷ extending over the edge of the window sill down to the ground.

G is a fireman's hook connected to the pole G' which is formed by a plurality of 25 pole lengths connected together by the bracket G². When removing the bracket B the hook of the pole G' is placed on one of the arms of the bracket B and the cord F⁷ is pulled so as to throw the inner hook end of 30 the bracket B out of engagement with the window ledge A³ and the bracket may then be removed through the window and lowered to the ground.

The connecting bracket G² shown in Fig. 35 3 comprises two members G⁴ and G⁵ hinged together at G⁶ and designed to encircle two

approaching ends of two adjacent pole lengths. The free sides of the members G⁴ and G⁵ are connected together by the swing hooks G⁷ engaging the projection G⁸. Although I show this form of clamp, of course, it will be understood that there are various forms which may be used which will accomplish the same result.

From this description it will be seen that 45 I have devised a very simple device whereby a fire escape apparatus may be easily placed in an upper story window of a building by a fireman so that the people may be easily and quickly lowered therefrom. 50

What I claim as my invention is:

1. A device of the kind described comprising a vertical plate, a looped bar, having one end terminating in a hook, a loop attached to said plate intermediate the ends thereof, a 55 plate pivoted at its lower end in said loop and having its upper end extending through said looped bar, the upper end of said vertical plate being arranged to slide on said looped bar.

2. A device of the kind described comprising a vertical plate a looped bar attached to said plate terminating at one end in a hook portion, a second plate pivoted at its lower end to said first named plate said piv- 65 ceted plate having its upper end extending through said looped bar.

JOHN COLLISON BROWN.
